Des. 211,947
Patented Aug. 13, 1968

211,947

AIR CIRCULATOR

Masaya Matsuyoshi and Masaru Furuzawa, Osaka, Takehiro Sugihara, Ibaragi, and Katsumi Shimoyama, Osaka, Japan, assignors to Matsushita Electric Industrial Co., Ltd., and Matsushita Seiko Co., Ltd., both of Osaka, Japan, both corporations of Japan

Filed July 10, 1967, Ser. No. 7,745

Claims priority, application Japan Jan. 26, 1967

Term of patent 14 years

(Cl. D23—156)

FIG. 1

FIG. 2

FIG. 3

FIG. 4

FIG. 5

FIG. 1 is a front elevational view of an air circulator showing our new design;

FIG. 2 is a top plan view thereof,

FIG. 3 is a left side elevational view thereof,

FIG. 4 is a top and front perspective view thereof, and

FIG. 5 is a bottom and rear perspective view thereof.

The dominant features of our new design reside in the full line portions.

We claim:

The ornamental design for an air circulator, as shown and described.
